PROCESS OF JUSTIFYING WITH HOT METAL.

1,090,818.

Specification of Letters Patent. Patented Mar. 17, 1914.

Original application filed September 27, 1912, Serial No. 722,710. Divided and this application filed May 26, 1913. Serial No. 769,855.

To all whom it may concern:

Be it known that I, RANDOLPH LANGSETH, a citizen of the United States, residing at Hammond, county of Lake, State of Indiana, have invented a certain new and useful Improvement in Processes of Justifying With Hot Metal, and declare the following to be a full, clear, and exact description of the same, such as will enable others skilled in the art to which it pertains to make and use the same, reference being had to the accompanying drawings, which form a part of this specification.

Cuts and the like are often supplied to the printer in a form which necessitates justifying in order to make them fit into the column or page scheme, the justifying being done by laying beside the cut filling pieces in sufficient numbers to produce with the 20 cut a piece of composition of the desired width; the justifying process being a slow one because of the necessity of selecting and trying the filling pieces so as to secure just the proper dimensions; and the typographical 25 material, with the piece of composition set into it being often weak and unstable instead of firm and solid, as it should be.

The object of my invention is to produce a simple and novel process whereby a piece 30 of composition may be justified quickly and with exactness, reducing the number of parts to a minimum and overcoming the objection of lack of stability and rigidity inherent in composition as heretofore justified. 35 The various features of novelty whereby my invention is characterized will herein-
after be pointed out with particularity in the claims; but, for a full understanding of my invention and of its objects and advantages, reference may be had to the following detailed description taken in connection with the accompanying drawing, which is a plan view of a machine adapted to be used to carry out my improved process.

Broadly speaking, my improved process consists in justifying with hot metal, the cut or other device being held within a form or mold having the exact dimensions of the space in the typographical material available therefor, and hot metal being poured into the form or mold at one or preferably two sides of the cut or other device. By making the form or mold of exactly the right width, the hot metal will be so shaped

that the piece of composition will fit accurately in the space available for it: there being no fitting and trying of filling pieces; and, because the piece of justified composition always is of exactly the right width and is composed of the smallest possible number of parts, solidity and rigidity is obtained when a piece of composition is set up with the rest of the typographical material. My process may of course be carried out with a simple apparatus of any kind, although in practice special machinery or apparatus will usually be employed in order to reduce the time and labor required for justifying to a minimum.

In the drawing I have illustrated the machine described and claimed in my application Ser. No. 722,710 of Sept. 27, 1912, of which this application is a division.

Referring to the drawing, 1 represents a flat table of a convenient height. At one end of the table is a melting pot, 3, adapted to contain molten metal for justifying; the pot being carried by a part, 4, secured to the table; and the metal in the pot being kept in a heated state by any suitable means such as a burner, 5, arranged below the pot. Along the front of the table is a low upwardly projecting wall or ledge, 6. A similar wall or ledge, 7, extends along one of the ends of the table. At the opposite end of the table preferably at the end at which the melting pot is situated is a detachable wall or ledge, 8, similar to the walls or ledges 6 and 7. In the arrangement shown, the wall or ledge 8 is pivotally connected or hinged at its rear end to the table, as indicated at 9, this arrangement permitting it to be swung around out of the way in order to remove the justified piece or pieces of composition as will hereinafter appear. The front end of the wall or ledge 8 and the adjacent end of the wall or ledge 6 are so shaped that when the member 8 is in its normal position, butting against the end of the member 6, a tight joint is produced between the two. The member 8 may be locked in its normal or closed position in any suitable way as, for example, by means of a pin, 10, inserted through registering openings in adjacent ends of the members 6 and 8. Upon the table and fitting accurately between the members 7 and 8, is a fourth shallow wall or ledge, 11, this

edge or wall being movable from and toward the member 6 and determining the width of a piece of composition. The upper faces of the members 7 and 8, along their inner edges, are preferably graduated as indicated at 12 and 13, respectively; the graduations permitting the movable wall or ledge to be accurately adjusted parallel with the opposite wall or ledge at any desired distance therefrom. The movable wall or ledge may be adjusted in any suitable manner. In the arrangement shown, I have connected to the member 11, near its ends, two long screws 14 and 15, which extend back across the table at right angles to the member 11. On the rear ends of the screws are nuts 16 and 17 respectively, suitably supported upon stationary brackets, 18, in such a manner that they are free to revolve but are held against axial movements. The nuts serve as the hubs of sprocket wheels 19 of which they form a part or to which they are secured. Mounted beneath the table, and extending from the front to the back is a revolute shaft, 20, having at its front end a crank or handle, 21, by which it may be turned. On the rear end of the shaft is a sprocket wheel, 22. An endless sprocket chain, 23, passes over the sprocket wheel 22 and around each of the sprocket wheels 19. It will be seen that by turning the crank or handle 21, both of the sprocket wheels 19 are turned in one direction or the other, rotating the nuts on the two screws and causing the screws to move axially and carry the movable wall or ledge 11 toward the front or the back of the table, as the case may be. The distance between the members 6 and 11 determines one of the dimensions of the piece of composition or of the mold in which it is produced and the other dimension is determined by one of the side walls, preferably the member 8; and a movable part lying between the members 6 and 11. The cuts or other devices are of course of various sizes and shapes, measured along the two axes lying at right angles to each other in the plane of their faces and furthermore, it is often possible to justify several different pieces of composition at the same time. It is further necessary to provide some means for effectively forming the fourth wall of the form or mold whose other three walls are portions of the members 6, 8 and 11, and it is desirable to have means for conveniently dividing the form or mold into a series of compartments lying side by side. To this end I have provided a series of metal plates graduated in length so as to provide a plate for each width which may at any time be desired, the plate of the proper length being set on edge between the members 6 and 11 before the member 11 is adjusted to its final position and the plate therefore serving both as a spacing device between the members 6 and 11 and as an end wall for the form or mold. In the drawings I have illustrated one of these plates, the same being indicated at 25. The top faces of the members 6 and 11, along their inner edges, may be provided with suitable scales 26 and 27 for the purpose of permitting the plates 25 to be set accurately at right angles to the members 6 and 11. I have also provided a series of thin metal strips or rules 28, each series preferably containing several units of the same length and the series as a whole being graduated to correspond with the series of plates 25. The strips or rules 28 are intended to be placed in the form or mold so as to divide it into a series of compartments each of which contains a cut and each of which produces a piece of accurately justified composition. In the drawing I have illustrated the apparatus as arranged to form five separate pieces of composition, there being five cuts, 31 to 35 inclusive within the mold or form bounded by the members 6, 8, 11 and 25; the cut 31 lying against the inner face of the member 8, the cut 35 lying against the inner face of the member 25, and there being a strip or rule 28 between each cut and the next cut. It is desirable that the loose plate 25 be pressed or supported in some manner in addition to being clamped between the members 6 and 11, and it is further desirable to have some means for pressing this plate laterally in order that there may be no looseness of the cuts or spacing strips or rules. To this end I have provided a rod or bar 36 extending transversely of the table between the members 6 and 11 and passing slidably through a block, 37, which is in turn slidably mounted in any suitable way upon the member 7 so as to have capacity for movements back and forth at right angles to the front of the table. The rod may be locked against movement in the block in any suitable way, as for example by providing the block with a thumb screw, 38, which may be screwed against the rod. The sliding connection between the block and the table may conveniently be secured by providing the member 7 with an elongated dovetailed slot, 39, into which fits a complementary projection on the block. Each of the plates 25 is provided on one side with a socket 41 for receiving the inner end of the rod 36. In adjusting the apparatus the block 37 is shifted so as to bring it halfway between the members 6 and 11, the set screw 38 is loosened, and the rod 36, then adjusted so as to fit its end into the socket in the plate 25. Then by pushing in on the rod the parts 31 to 35 inclusive and the spacing strips or rules 28 are clamped solidly between the members 8 and 25. Since the rod 36 should lie halfway be-

tween the members 6 and 11, it follows that the rod must be shifted back and forth through half the distance traveled by the member 11 in making adjustments and therefore the block 37 may conveniently be connected to the actuating means for the member 11 in such a way as always to keep the block and the rod in the proper position, regardless of the distance between the members 6 and 11. In the arrangement shown, the block 37 is carried upon the front end of a screw rod 43 which passes back through a stationary nut 44 at the rear end of the table. On the rear end of the screw rod is a gear wheel 45 which meshes with an elongated pinion 46 secured to or forming a part of the nut 16; the gear wheel having twice as many teeth as the pinion and the threads on the members 14 and 43 being in opposite direction. It will be seen that by this arrangement the block 37 is always adjusted in the same direction as the member 11, when the latter is moved, but travels only through half the distance through which the member 11 passes.

The series of plates 25 and rules or strips 28 are preferably carried in a suitable rack 47 mounted upon the table at the back thereof; the rack being divided into a series of graduated compartments 48 each of which is adapted to contain one of the plates 25 and the set of spacing strips or rules having the same length as the plate. This arrangement makes it easy for the operator to select the proper material for making the form or mold.

After the cuts have been set up as illustrated in the drawing, molten metal is taken from the pot and is poured into the spaces between the several cuts and the members 6 and 11. The hot metal completely fills the space in each compartment so that when the metal cools and solidifies, each compartment contains a piece of composition accurately justified. When the justifying metal has

cooled, the member 8 is swung around as indicated by the dotted lines in the drawing, and, upon releasing the pressure of the member 11 upon the ends of the members 25 and 28 and loosening the set screw 38, the rod 36 may be used to push the justified matter off the side of the table upon the auxiliary table formed by the member 4. After the printing has been completed, the justifying pieces may be remelted and thus be used over and over again.

It will thus be seen that I have produced a simple and efficient process whereby it is possible to justify cuts or the like quickly and accurately regardless of the width of the space available therefor in the typographical matter and in such a way as to make the typographical matter solid and firm.

I claim:

1. The process of justifying which consists in forming about the cut a mold two of whose sides engage with the ends of the cut and project beyond the sides of the cut so as to leave a space on two opposed sides, and filling said spaces with the molten metal.
2. The process of justifying a piece of composition which consists in casting beside the same one or more detached justifying blocks.
3. The process of justifying a piece of composition which consists in placing the same in a mold having a length equal to the piece of composition to be justified and a width equal to the width of the space in which the piece of composition is to be set in the typographical matter and then pouring molten metal into the mold beside the piece of composition.

In testimony whereof, I sign this specification in the presence of two witnesses.

RANDOLPH LANGSETH.
